AUTOMATIC FIREARM

Gotthard End, Schaffhausen, Switzerland, assignor to Schweizerische Industrie-Gesellschaft, Neuhausen, (Ct. Schaffhausen, Switzerland), a corporation of Switzerland

Original application January 25, 1934, Serial No. 708,305. Divided and this application July 6, 1936, Serial No. 89,046. In Switzerland February 10, 1933

5 Claims.

(Cl. 42—3)

The invention relates to a new and improved automatic fire-arm of great firing power as described in the co-pending patent application Serial No. 708,305 Patent No. 2,052,287 of which the following is a divisional application.

The main object of the invention consists in the provision of an automatic fire-arm being suitable for transport and capable of being quickly set ready for action.

10 A further object is the provision of a magazine arrangement for fire-arms which is reliable and of simple mechanism and operation.

The magazine according to this invention is provided with a large pivoted or detachable box magazine which for use of the fire-arm is placed into the charging opening of the fire-arm in a position substantially at right angles to the barrel while, when the fire-arm is not required for use, the magazine is placed into a position substantially 15 in a plane parallel to the barrel in front of or behind the charging opening but directly adjacent the latter. The characteristic feature of the invention is that the fire-arm and box magazine are so constructed that the magazine 20 is housed in the stock of the fire-arm.

The increased firing power of an automatic fire-arm necessitates a large interchangeable magazine. The want of handiness in transport hitherto caused thereby is obviated as the magazine 25 is pivotally or detachably mounted on the fire-arm and is adapted to be folded into the stock when not in use.

The invention will now be described with reference to the accompanying drawing wherein:

30 Fig. 1 shows a fire-arm in section with the magazine in the position when the fire-arm is required for use.

Fig. 2 shows the fire-arm with the magazine in the inoperative position.

40 Fig. 3 shows a second example of construction of the fire-arm.

As shown in Fig. 2 the magazine 10 when not required for use lies along the barrel 1 and the stock 27 of the weapon. The length of barrel is such that it extends beyond the front portion 29 of the stock 27 which receives the magazine 10. The magazine 10, which by means of the bush 9 rocks about the pin 8, fits snugly into a recess in the stock 27 in the swung-in position (Fig. 2) lying approximately parallel to the barrel 1, the portion 29 covering it at the front. The magazine 10 is easily interchangeable. By corresponding replacement of the barrel 1, bush 9 and magazine 10 the fire-arm can be used with cartridges of different calibres, e. g. 7.63, 7.65 and

9 mm. The magazine is held in the recess 28 by a cover 30 pivoted at 33. The cover 30 is provided with two side-pieces 31 which, when the magazine is in the operative position partly embrace this and when the magazine is in the inoperative position serve, together with the cover 30, to close the charging opening completely. The cover is pressed into the closing position by a spring 32.

In Fig. 2 the fire-arm is shown with open breech 10 and at "safety". When the safety catch 34 is moved to the release position (position F, Fig. 1), it rotates about its axis 35 and pushes a cover bar 37, pivoted thereto at 36, towards the magazine. During this movement the bar 37 engages 15 a projection 38 on the cover 30 thus rocking the latter downwardly and releasing the bush 9. The latter drops under the action of gravity or of a spring, not shown, together with the magazine 10 rocks about its pivot 8 opening the cover 30, 20 and assuming the position shown in Fig. 1. In this position the bush 9 engages with a hook 39 on the cover 30. By moving the safety catch 34 from "safe" (position S) to "fire" (position F) the rifle is ready for firing. 25

The empty magazine 10 may be replaced readily by a full one. The magazine 10, when the safety catch 34 is in the position S "safe", may be left in the extended operating position or be rocked into the recess 28. For the latter purpose, 30 the cover 30 must be drawn slightly backwards so that its hook 39 releases the bush. When the bush has been moved into the recess 28, the upper end is engaged by the cover 30, thus locking it. This locking, however, cannot occur until the 35 safety catch 34 has been moved to the position S "safe". When the magazine is in the recess 28 it is retained by the locking pawl 11 and cannot be disengaged accidentally, so that the magazine 10 cannot be lost. 40

When it is not desirable to make the cover 30 dependent on the position of the safety catch, or if the safety catch is arranged in such a manner that the cover 30 is independent thereof, the cover bar 37 may be omitted. The side pieces 31 45 of cover 30 serve as a grip to facilitate moving the cover 30 which can be moved independently of the safety catch 34.

In the example of construction according to Fig. 3, when the magazine 10 is not required 50 for use it also in this case rests in a recess 28 of the stock. One end thereof rests on a support 41 secured to the portion 29 while its other end is engaged by a projection on the locking catch 11. When the magazine is to be placed into the 55

bush the catch 11 is pressed so as to disengage its projection from the magazine. The latter is thus released and can be inserted into the bush 9. If desired the catch 11 could be associated with the safety catch 34 in the same way as the cover 30 in the example of construction shown in Figs. 1 and 2.

A cover may be fitted in a similar manner to the previous arrangement but simply for closing the magazine opening. The arrangement according to Fig. 3 has the advantage that in addition to the long magazine 10 in the recess of the stock, a short magazine 40 may be fitted into the bush 9 as shown by dotted lines, without affecting the portability of the rifle. Independently of the position of the safety catch and breech block, this short magazine may be replaced by the long magazine and placed into a recess in the butt of the stock when not required for use.

20. What I claim is:—

1. An automatic fire-arm comprising in combination with the barrel, a stock provided with a magazine receiving opening and extending with its front portion along a portion of said barrel, 25 an exchangeable magazine positioned at a right angle to the barrel when inserted in said opening, the front portion of said stock being provided with a longitudinal recess adapted to receive and store said magazine lengthwise in an 30 inoperative position when it is removed from its operative position in said opening, one end of said recess being located immediately adjacent said magazine receiving opening, and pivotally supported means for locking said magazine in its 35 operative position and for holding said magazine in said longitudinal recess.

2. An automatic fire-arm comprising in combination with the barrel, a breech provided with a cartridge receiving opening, a stock extending 40 with its front portion past said breech and along a portion of said barrel, said front portion of said stock being provided with a longitudinal recess, a magazine bush pivoted to said breech, an exchangeable magazine adapted to be inserted 45 in said magazine bush, said magazine bush being pivotally supported in a manner for moving said magazine when inserted in said bush from its operative position in which it is in communication with said cartridge receiving opening and 50 at a right angle to the barrel into its inoperative position in which the magazine is positioned lengthwise in said longitudinal recess in the stock.

3. An automatic fire-arm comprising in combination with the barrel, a breech provided with a cartridge receiving opening, a stock extending 55 with its front portion past said breech and along

a portion of said barrel, said front portion of said stock being provided with a longitudinal recess, a magazine bush pivoted to said breech, an exchangeable magazine adapted to be inserted in said magazine bush, said magazine bush being pivotally supported in a manner for moving said magazine when inserted in said bush from its operative position in which it is in communication with said cartridge receiving opening and at a right angle to the barrel into its inoperative position in which the magazine is positioned lengthwise in said longitudinal recess in the stock, and a spring actuated member adapted to lock the magazine bush in its two alternate positions, in one of which it supports the magazine in operative position and in the other one it holds the magazine in said recess. 5

4. An automatic fire-arm as claimed in claim 3, in which said spring actuated member comprises a closure plate which in the inoperative position of the magazine closes that portion of the recess which has been vacated by the magazine bush and lies immediately below said cartridge receiving opening. 10

5. An automatic fire-arm comprising in combination with the barrel, a breech provided with

a cartridge receiving opening, a stock extending with its front portion past said breech and along a portion of said barrel, said front portion of said stock being provided with a longitudinal recess, 30 a magazine bush pivoted to said breech, an exchangeable magazine adapted to be inserted in said magazine bush, said magazine bush being pivotally supported in a manner for moving said magazine when inserted in said bush from its 35 operative position in which it is in communication with said cartridge receiving opening and at a right angle to the barrel into its inoperative position in which the magazine is positioned lengthwise in said longitudinal recess in the stock, 40 a spring actuated member adapted to lock the magazine bush in its two alternate positions, in one of which it supports the magazine in operative position and in the other one it holds the magazine in said recess, and a safety catch for 45 said means being operatively connected with a member adapted to release said spring actuated member from the position in which it locks the magazine bush in inoperative position, said spring actuated member being released when said safety catch is shifted to firing position, the released magazine bush including said magazine thereupon moving by gravity in operative position at a right angle to the barrel. 50

GOTTHARD END. 55
